[57] CLAIM

The ornamental design for a combined ceiling fan canopy, support rod, motor housing and light fixture unit, as shown and described.

DESCRIPTION

FIG. 1 is a perspective view of a combined ceiling fan canopy, support rod, motor housing and light fixture unit illustrating my new design;

FIG. 2 is an additional perspective view of the combined ceiling fan canopy, support rod, motor housing and light fixture unit shown in FIG. 1 with the environmental structure removed therefrom;

FIG. 3 is a front view thereof;

FIG. 4 is a right-side view thereof;

FIG. 5 is a rear view thereof;

FIG. 6 is a left-side view thereof;

FIG. 7 is a top view thereof; and,

FIG. 8 is a bottom view thereof.

The broken lines shown in FIG. 1 are illustrative of environmental structure only and form no part of the claimed design.
